(57) **CLAIM**

The ornamental design for a hole cutter tip, as shown and described.

DESCRIPTION

FIG. 1 is a front perspective view of a hole cutter tip showing my new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof;

FIG. 9 is an enlarged cross-sectional view taken along line 9-9 in FIG. 3; and,

FIG. 10 is a referential perspective view of the front and rear of an identical hole cutter tip showing the tip in use on a hole cutter shown in broken lines.

The broken lines are shown for illustrative purposes only and form no part of the claimed design.

1 Claim, 4 Drawing Sheets
